LAMP OR SIMILAR ARTICLE

Ruth Greenspan, New York, N. Y., assignor to Wilmar Company Inc., New York, N. Y., a corporation of New York

Application October 27, 1955, Serial No. 38,587

Term of patent 7 years

(Cl. D48—20)

Fig. 1.

Fig. 2.

Fig. 3.

Fig. 1 is a front elevational view of a lamp showing my new design;

Fig. 2 is a rear view of said lamp; and

Fig. 3 is an enlarged sectional view taken substantially along the line 3—3 of Fig. 1.

The dominant features of my design are shown in full lines.

I claim:

The ornamental design for a lamp or similar article, substantially as shown and described.
